UNITED STATES PATENT OFFICE.

CARL VON REIN, OF RUDOLSTADT, ASSIGNOR TO TUNKER & RUH, OF CARLSRUHE, GERMANY.

SEWING-MACHINE.

SPECIFICATION forming part of Letters Patent No. 274,381, dated March 20, 1883.

Application filed August 26, 1882. (Model.)

To all whom it may concern:

Be it known that I, CARL VON REIN, a subject of the Emperor of Germany, and resident at Rudolstadt, Germany, have invented new and useful Improvements in Sewing-Machines, of which the following is a specification.

The object of my invention is to provide a new and improved sewing-machine which makes a double lock-stitch and which sews directly from two spools of thread.

The invention consists in a rotary spool-holder moving in a circular track below the sewing-plate and operated by driving-arms attached to the end of the driving-shaft, which spool-holder is provided with a cage for holding the spool, the said cage being provided with a pivoted frame-bar to permit opening the cage to place a spool therein.

The invention further consists in a vertically and transversely movable frame surrounding a cam on the driving-shaft, which frame is connected by a slotted lever with a lever carrying the feeder-teeth, and operates the said lever carrying the feeder-teeth. The fulcrum-pivot of the slotted lever can be adjusted and the length of the stitch will be varied according to the adjustment of the said pivot.

The invention also consists in details of construction and combination of parts, as will be fully described and set forth hereinafter.

Reference is to be had to the accompanying drawings, forming part of this specification, in which similar letters of reference indicate corresponding parts in all the figures.

Figure 1 is a longitudinal view of the bottom thread or spool holder of my improved sewing-machine, parts being shown broken out. Fig. 2 is a plan view of the same, parts being shown broken out and in section. Fig. 3 is a cross-sectional elevation of the same on the line *y*-*y*, Fig. 1. Fig. 4 is a longitudinal elevation of the same, showing the manner of forming the stitch. Fig. 5 is a cross-sectional elevation on the line *x*-*x*, Fig. 2, showing the cam. Fig. 6 is a longitudinal sectional elevation of the spool-holder.

A bracket-piece, *A*, projects downward from the sewing-machine frame below the sewing-plate *B*, and in the said bracket-piece *A* the shaft *C* is journaled. The bracket-piece *A* is

provided with a series of arms, *A'*, which hold a circular track-frame, *D*, provided along its inner edge with a groove, *a*, adapted to receive the beveled edges *b* of the spool-holder *E*. On the shaft *C*, near one end thereof, a cam-wheel, *C'*, is mounted, which is surrounded by a box, *F*, provided with two downwardly-projecting arms, *F'* and *F''*, of which the arm *F''* is provided at its lower end with a fork, *f*, having guide-slots *g*, into which a rod, *h*, passes, which projects from an arm, *j*, of the ring-frame *D*, so that when the cam-wheel *C'* rotates it moves the box *F* backward and forward, and the box and its arms will be guided by the forked prongs *f* on the lower end of the arm *F''*. The other arm, *F'*, is pivoted to the lower end of a longitudinally-slotted lever, *G*, which is held by an adjustable pivot, *H*, to a longitudinally-slotted downwardly-projecting arm, *J*, of the ring *D*. The pivot *H* is movably connected by a slot (seen in dotted lines in Fig. 1) to a lever, *K*, which is pivoted to the ring *D*, and permits of moving the pivot *H* higher or lower, as may be desired, the pivot being held at the point of adjustment by screwing it tightly in place, it being provided with a screw-threaded portion entering a female screw-threaded portion. The upper end of the lever *G* is pivoted to a guided lever, *L*, to which the feeder-teeth *l* are attached. At the end of the lever *L* opposite the one pivoted to the lever *G* the said lever *L* is provided with a longitudinal slot, into which a pin, *l'*, in the frame *D* passes, so that the said lever *L* will have a reciprocating and a rocking motion. The feeder-teeth *l* are operated by the lever *L*, which in turn is operated by the slotted lever *G*. If the pivot *H* is moved down to the lower part of the slotted lever *G*, the reciprocating movement of the teeth will be long, and long stitches will be formed, and if the pivot *H* is raised the length of the stitches will be decreased correspondingly.

The spool-holder *E* is placed within the ring-frame *D*, the beveled edges *b* of the spool-holder passing into the beveled grooved edges *a* of the ring-frame *D*. Two arms, *M*, the ends of which are curved, project from the end of the shaft *C* into the ring-frame *D*, and serve to turn the spool-holder around in the said

frame. The spool-holder E consists of a semi-circular plate, which is provided at one end with a curved beveled point or nose, *m*. Part of the semicircular plate or disk forming the spool-holder is cut out to form a recess for the spool, and the rods *n*, which are formed by cutting out the plate, form a cage for receiving the spool O. The ends of the cage are beveled, and thereby a beveled head, *o*, will be formed near the point *m* of the spool-holder. One of the bars *p* of the cage for receiving the spool is pivoted to the head *o*, and at its opposite end is provided with a hook, *q*, which passes through an aperture, *r*, in the plate of the spool-holder. The said pivoted cage-bar *p* is provided with two curved side arms, *p'*, which complete the cage. Conical blocks P are placed in the ends of the spool O, and a spindle, Q, is passed through the said blocks and through the spool. One end of the said spindle Q is passed into a spring-socket, R, and the other is passed into a fixed socket, R', so that the spool can easily be removed by pressing the spring-socket R inward and withdrawing the opposite end from the fixed socket. The thread passes from the spool through the slot *t* in the spool-holding disk, and then through apertures in the pivoted cage-bar *p*, and then through the plate B.

The operation is as follows: As soon as the thread has formed a loop by the upward movement of the needle, the point *m* of the thread or spool holder E enters the said loop, and in turning in the direction of the arrow *a'* the loop lays itself on both sides of the round head *o*, and is opened wide enough for the thread-holding cage to pass through. At this moment the thread is drawn taut, and the thread-holder must be slightly raised by the thread in order that the thread may pass between the driving-arm M and the spool-holder E. The thread is still further drawn upon and the loop arrives at the second driving-arm, M, which it passes in the same manner. The loop having now passed the spool-holder, the thread of the latter will be within the loop, which can now be drawn up. The cam C' acts upon the box F, carrying the arms F' F'', one of which moves the lever G, which in turn rocks and reciprocates the feeder-lever L, moving the feeding-teeth *l* to carry the work along. The thread is drawn taut by the spool-holder pressing it out of the straight line with the stitch-plate. The knotting of the thread is the same as in the ordinary shuttle-machine, the rest of the mechanism being the same as that in general use at present.

Having thus described my invention, what I claim as new, and desire to secure by Letters Patent, is—

1. In a sewing-machine, a spool-holder which runs in a circular guide or track and is at the same time the rotating thread-carrying hook, said spool-holder being driven by two side arms, and consisting of a flat segment of a circle and of a skeleton holder having curved side strips or arms to effect the unobstructed pas-

sage of the spool and spool-holder through the loop of the upper thread, one of said strips being provided with a hinge and catch to permit it to be swung back for the removal or replacement of a spool, substantially as and for the purpose set forth.

2. In a sewing-machine, the flat segmental spool-holder provided with the thread-carrying hook and running in a circular grooved track, said spool-holder having the segmental thread-slot *t* in its flat portion and the series of triangularly-arranged thread-apertures in one of the strips of its skeleton portion, as shown and described, and for the purpose set forth.

3. In a sewing-machine, the combination, with the shaft provided with a cam, of a box surrounding said cam and provided with arms, of which one is guided to reciprocate the box and arms, the other being connected by means of a lever with a rocking and sliding bar carrying the cloth-feeder teeth, substantially as and for the purpose set forth.

4. In a sewing-machine, the combination, with the shaft C, provided with a cam, C', of the box F, provided with the arms F' F'', the lever G, the arm J, the pivot H, the lever L, pivoted to the lever G and carrying the feeder-teeth *l*, substantially as and for the purpose set forth.

5. In a sewing-machine, the combination, with a shaft provided with a cam-wheel, of a box surrounding the said cam-wheel and provided with arms, of which one is guided to reciprocate the box and the arms, the other being connected by means of a pivoted lever, the oscillation of which can be adjusted, with a rocking and sliding bar to which the cloth-feeder teeth are attached, substantially as herein shown and described, and for the purpose set forth.

6. In a sewing-machine, the combination, with the shaft C, provided with a cam, C', of the box F, provided with the arms F' and F'', the slotted lever G, the slotted arm J, the adjustable pivot H, the lever L, pivoted at the other end of the lever G, and the feeder-teeth *l*, attached to the lever L, substantially as herein shown and described, and for the purpose set forth.

7. In a sewing-machine, the combination, with the shaft C, provided with the cam C', of the box F, provided with the arms F' and F'', the fork *f*, formed at the lower end of the arm F'', the rod *h*, the slotted lever G, pivoted to the end of the arm F', the slotted arm J, the adjustable pivot H, the rocking and reciprocating lever L, and the feeder-teeth *l*, substantially as herein shown and described, and for the purpose set forth.

In testimony whereof I have signed my name to this specification in the presence of two subscribing witnesses.

CARL V. REIN.
